UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

REED-TYPE SPRAY NOZZLE.

Application filed January 7, 1926. Serial No. 79,910.

- My invention relates to spray nozzles and, particularly to those adapted for direct injection of fuel into internal combustion motors where the fuel is injected directly under pressure and without any compressed air or other agents accompanying it, although obviously my spray nozzle may be used wherever it is desirable to spray or atomize or comminute a liquid.
- 10 It will be understood that this spray may be used in an engine or elsewhere; that it may be directly injected into the chamber or place where it is going to be used or it may be fixed as it is injected or produced or subsequently, with gas or other material, it might, for instance, be injected into an ordinary type of carburetor in which, in such case, the fuel instead of being sucked into the air passage would be injected into 20 it, and of course, any desired modification of this might be provided.
- 25 The nature of my nozzle is such that it is normally held closed and is opened only by the direct pressure of the liquid behind it. The opening is effected by the mass deformation of one or more of the parts of which the valve is composed. In the particular example herewith set forth, I employ a steel valve disc which is deformed 30 by the pressure of the fuel against it and thus allows the fuel to be forced into the combustion chamber of the motor.
- 35 My invention is illustrated in the accompanying drawings where:
- 35 Figure 1 is a vertical section showing my valve in place;
- Figure 2 is a section on the line 2—2 of Figure 1;
- 40 Figure 3 is a detail section, on an enlarged scale, through a modified form of my device;
- 45 Figure 4 is a plan view of the valve disc of Figure 3 with parts cut away;
- Figure 5 is a similar plan view of a modified form.
- 50 Figure 6 is a section along the line 6—6 of Figure 5.
- Figure 7 is a plan view of one of the two mating spray discs.
- 55 Figure 8 is a plan view of a modified reinforcing washer arrangement.
- Like parts are indicated by like characters in all the figures.
- A is a hollow spray head to which liquid under pressure may be fed through a pipe
- A¹. A² is a chamber and it may be an engine cylinder or any other kind of a chamber into which the spray head is screw threaded or otherwise attached and into which the spray is adapted to be discharged. 60 B¹ and B² are two spray semi-circular mating disc segments; they close the end of the spray head, being seated upon the packing washer B¹ by a screw threaded cap B². B³ is an apertured reinforcing washer adapted 65 to support the spray disc or segments. The walls of the aperture of said washer approaching more closely to the line of cleavage between the discs at the center than elsewhere. This particular arrangement of 70 the reinforcing washer will be used of course only when the spray or liquid is to pass out through a relatively elongated crack, because under such conditions it is necessary to have the space between the 75 meeting edges of the discs approximately constant or at least not too widely divergent between a maximum and minimum opening.
- The modified form shown in Figures 3 and 4, however, dispenses with the reinforcing washer B³ for the purpose of suggesting that under some conditions this washer might not be necessary and I have shown an overlying apertured packing washer C. This washer is held against the segmental 80 disc by the pressure of the liquid and exposes only a relatively short portion of the joint between the two discs so that when pressure tends to force liquid out between the discs the liquid can pass only at the center and thus a relatively short spray is produced. It will be understood that this packing disc C is without any spring action 85 but it merely serves to limit the point at which flow may take place and that it may be used with or without the apertured reinforcing washer.
- In Figures 5 and 6, the spring segments are weakened by the counter-sunk hole D in Figure 7. This weakened disc is shown 90 without the overlying packing disc, the idea being that when pressure is put upon the liquid the spray will pass through only at the point where the weakening has taken place, since the resistance to flow is greatly 95 diminished at that point.
- In the modified form of Figure 8 the reinforcing disc or washer has a central circular aperture. In this case the washer might serve both as a reinforcing and as a 100
- 105
- 110

packing or limiting washer to limit the length of the space between the mating discs through which the spray is discharged.

5 The use and operation of my invention are as follows:

Whenever liquid under pressure is introduced into the hollow spray head and the pressure is raised above a certain predetermined point, the two spring plates will be forced apart to permit liquid to rush out under pressure from between them. If these discs are shown in Figures 1 and 2 without any support, there might be an irregular spray action resultant upon too great a strain on the thin spring discs and the reinforcing washer which supports them in various ways as indicated prevents this, equalizes the strain and perhaps in some cases limits the point at which the spray action can take place.

Under some conditions it is best to have the spray pass out only through a very short passage, and to make this possible, I provide the thin plate which rests upon the spring discs and is perforated to expose only a short portion of the crack between the edges of the discs.

These discs are very sensitive and experience shows that by merely weakening or thinning out the discs on one side near the crack, the spray can in this way be localized.

Experience shows under some conditions it is desirable to have the edges of the discs actually in contact. Under other conditions it might be desirable to have the discs so positioned that their edges are just out of contact and even when this is the case experience shows that perhaps on account of surface tension or capillarity or perhaps for some other reason which we do not need to go into at this time, that drooling or leakage of the liquid will not take place.

I claim:

- 45 1. In an injection valve, a composite valve disc composed of a plurality of segments normally tangent.
2. In an injection valve, a composite valve disc composed of a plurality of segments normally tangent, and additional means for supporting said disc.
- 50 3. In an injection valve, a composite valve disc composed of a plurality of segments normally tangent, and additional means for supporting said disc, comprising an apertured supporting disc.
4. In an injection valve, a composite valve disc composed of a plurality of normally tangent segments, and an apertured supporting disc therefor and in contact therewith.
5. In an injection valve, the combination of a composite valve disc composed of a plurality of segments normally tangent, 55 with a supporting cap therefor, having an

opening in it substantially in register with the union between said segments.

6. A spray head comprising a supporting housing, having a liquid containing chamber therein, a closure for said chamber comprising a plurality of spring plates arranged in a single plane and means for holding them edge to edge.

7. In a spray nozzle two spring plates and means for holding them in position in the same plane with their opposed edges in contact throughout their length.

8. A spray head comprising a supporting housing having a liquid containing chamber therein, a closure for said chamber comprising a plurality of spring plates arranged in a single plane and means for holding them edge to edge, means adjacent but slightly removed from their opposed edges for supporting said plates.

9. In a spray nozzle, two spring plates and means for holding them in position in the same plane with their opposed edges in contact throughout their length, means adjacent but slightly removed from their opposed edges for supporting said plates.

10. In a spray nozzle, two spring plates arranged with opposed edges in contact and located in the same plane, means for holding the plates rigidly in position.

11. In a spray nozzle, two spring plates arranged with opposed edges in contact and located in the same plane, means for holding the plates rigidly in position, a continuous plate resting upon said separate plates and closing the crack between them except throughout a short portion of its length.

12. A spray head comprising a housing adapted to contain liquid under pressure, a nozzle disk closing said housing made up of a plurality of separate spring elements engaging along their edges and means for holding them in position.

13. A spray head comprising a housing adapted to contain liquid under pressure, a nozzle disk closing said housing made up of a plurality of separate spring elements engaging along their edges, means for holding them in position, and means for positively preventing the discharge of liquid from between said spring elements except throughout a short portion of the crack between them.

14. A spray head comprising a housing adapted to contain liquid under pressure, a nozzle disk closing said housing made up of a plurality of separate spring elements engaging along their edges, means for holding them in position, and means for positively preventing the discharge of liquid from between said spring elements except throughout a short portion of the crack between them, said means comprising an apertured disk resting upon said spring elements.

15. A spray nozzle comprising two plates

having opposed edges in contact and located in the same plane, means for holding said plates rigidly in position and a third plate resting against them in a parallel plane apertured at a point in line with the joint between the first two plates.

16. In a spray nozzle, two plates arranged edge to edge and located in the same plane, means for holding said plates rigidly in position so that their abutting edges are in

close and intimate contact and a plate in engagement with said two plates, apertured in line with the joint between the first two plates and means for holding all three plates rigidly together at their common peripheries.

Signed at Chicago, county of Cook and State of Illinois, this 4th day of January, 1926.

PHILIP LANE SCOTT.
